RAIL CLAMP

David T. Alexander, Windsor, Ontario, Canada

Application July 21, 1937, Serial No. 154,915

2 Claims. (Cl. 238—335)

This invention is a rail clamp particularly intended for use in fastening the rails forming the runway of a traveling crane.

Referring to the accompanying drawing:

5 Figure 1 is a top view.

Figure 2 is an end view.

Figure 3 is a side view.

The rail 1 rests on a channel 2 carried by a beam 3. In view of the extremely wide tread 10 of a crane runway, the rail 1 must be very accurately aligned and must be positively held against lateral shifting.

The clamp itself constitutes a rectangular part 4 of sufficient width to provide room for two bolt holes 5, this part being constructed to bridge from the top of the base of the rail to the top of the channel 2, bolts 6 passed through the bolt holes and through holes formed in the channel 2 and the flange of the beam 3 serving to cause this 20 part to firmly hold the rail against upward displacement.

This rectangular part 4 has an upwardly extending end 4^a in which a transverse screw-hole is formed, a setscrew 7 provided with a lock-nut 25 8 being threaded through this hole. The end part 4^a is so arranged respecting the part 4 as to cause the setscrew 7 to bear against the web of the rail 1.

As shown by the drawing, the clamp being 30 described is used in pairs, with the two clamps of each pair positioned opposite one another and the setscrews 7 in substantial alignment. When the bolts 6 are slightly loose it is possible to shift the rail laterally by screwing in one of the set-screws and unscrewing the other. In this manner very accurate alignment of the rail may be effected. After this, the bolts 6 may be tightened as much as possible and the lock-nuts 8 screwed against the ends 4^a. In this manner the 40 rail may be anchored without any loss of alignment.

During the service life of the installation it is

impossible for the rail to shift out of alignment unless there is actual breakage of some of the parts involved. Proper design will, of course, eliminate this possibility.

I claim:

1. A rail clamp comprising a part for bridging between the top of the base of a rail and the support on which the rail rests, said part having an upwardly extending portion in which a transverse screw hole is formed, a screw provided with a lock-nut being threaded through said hole and said part being provided with releasable hold-down means, said screw being adapted to engage the web of the rail fastened by said clamp and to be used to effect both rail aligning movement 15 and to hold said rail against lateral shifting when the same is aligned and said clamp is held down by said means, the latter being capable of holding said clamp against movement transverse of the rail when loosened to permit rail aligning 20 movement.

2. A rail fastening including the combination of a rail clip for holding the base of a rail down on a suitable support but at times permitting the base of the rail to be free for transverse movement independent of the clip, releasable means for applying downward pressure on said clip, said means holding said clip against movement transverse of the rail both when tightened, and also when loosened to relieve the downward 30 pressure on said clip, and means engaging said clip and extending to engage the web of a rail whose base is held down by the latter, the last named means being in screw-threaded engagement with said clip whereby it may be used to 35 transversely shift the rail when the first named means is loosened to relieve downward pressure on said clip, said first named means functioning to hold said clip against movement transverse of said rail whereby to permit said operation of said 40 last named means.

DAVID T. ALEXANDER.
